(57) **CLAIM**

We claim the ornamental design for an integrated control unit for a vehicle, as shown and described.

DESCRIPTION

FIG. 1 is a perspective view of an integrated control unit for a vehicle, showing our new, original and ornamental design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

In the drawings, the broken lines depict unclaimed subject matter only and form no part of the claimed design.
